UNITED STATES PATENT OFFICE.

SARAH D. ROTHSTEIN, OF GAINESVILLE, GEORGIA.

TOILET ACCESSORY.

No Drawing. Application filed April 2, 1927. Serial No. 180,626.

This invention relates to a massaging device. It is the object of the invention to provide a device which is to be utilized for massaging the face or other parts of the body. A further object of the invention is to provide a massaging device which may be used for rubbing down the skin of the face or of other parts of the body without causing any irritation of the skin, but having the beneficial effect of smoothing the skin and reducing the wrinkles.

The device may be used dry without the application of any cleansing agents such as soaps or creams, or, if desired, the device may also be used in the manner in which ordinary wash cloths or wash pads are used. In the latter case, the device is used for the application of soaps or creams by the aid of a rubbing action which serves to smoothen the skin, and reduce the wrinkles thereof simultaneously with the cleansing action.

One specific embodiment of the invention takes the form of a sheet of textile fabric which is impregnated with coagulated albumen or albuminous material. The albuminous material imparts to the fabric a certain degree of stiffness accompanied by a desirable amount of resiliency and flexibility. The pad having impregnated therein the albuminous material presents a surface having all of its pores filled with the albuminous material. The result is that the pad while it presents a wrinkled surface nevertheless presents a surface that is smooth and continuous and is devoid of any sharp points. This surface when applied to the skin with a rubbing action will not cause any irritation but will on the contrary, have the effect of smoothing the skin and reducing the wrinkles.

The desirable effects are due in part to the physical characteristics of the surface and

are probably also due in part to the chemical constitution of the surface. The latter point is based on the theory that intimate contact between the albuminous surface of the pad and the skin has a tonic or invigorating effect upon the skin.

The textile material may be of any thickness desired and may be either of the woven or knitted type or of any desired structure. I prefer, however, to utilize a thin sheet of woven textile fabric and to impregnate same throughout its body with a coagulated albuminous material. If desired, however, the fabric may be of substantial thickness and it may be so treated and impregnated that only a thin layer of the material below its surface is impregnated with the coagulated albuminous material. Where it is desired to utilize the invention in the form of a wash cloth or wash pad, it is perhaps preferable to make the same out of a thick textile fabric. If, however, it is to be used merely as a massaging device in its dry state, without the application of any soaps or creams it may be made of a sheet of thin textile fabric.

Having described my invention, I do not wish to be limited to the specific embodiment thereof described herein, many modifications thereof within the scope of the claims appended hereto being apparent to those skilled in the art.

I claim:

1. A massaging device comprising a textile fabric having a wrinkled surface and having a surfacing of albuminous material.
2. A massaging device comprising a textile fabric impregnated with coagulated albuminous material, and having a wrinkled surface.

In witness whereof I have hereunto affixed my signature.

SARAH D. ROTHSTEIN.
